UNITED STATES PATENT OFFICE.

CHRISTIAN SIMON, OF ESSEN-ON-THE-RUHR, GERMANY.

COAL-JIGGER.

1,082,102.

Specification of Letters Patent.

Patented Dec. 23, 1913.

Application filed September 4, 1912. Serial No. 718,550.

To all whom it may concern:

Be it known that I, CHRISTIAN SIMON, engineer, a subject of the German Emperor, residing at Essen-on-the-Ruhr, Germany, 5 have invented certain new and useful Improvements in Coal-Jiggers, of which the following is a specification.

In the dressing of coals by means of jiggers it has proved to be of advantage to 10 eliminate first a part of the rubbles, especially the heavier ones, by means of a stone bed, through the jiggling sieve, while the remaining lighter rubbles are being removed in a compartment close behind that, 15 by a so called discharge device, having its position above the jiggling sieve. In this way the heavier rubbles are prevented from disturbing the issue of the lighter ones at the discharging device. It has proved to 20 be of great disadvantage that the dam be massive in those jiggers, the floods carrying away the stones over the dam. If, in order to prevent this, the dam is made higher, the light rubbles especially accumulate, 25 the first compartment is then too heavily charged and does not work at all. Instead of massive dams wire nets have also been employed, which are fastened between the sieve and a vertical bar, placed above it. 30 By this arrangement the resistance is too great and the material accumulates before the meshes, especially if the first compartment is too heavily charged. In this case the first compartment does not work. If 35 on the other hand the dam is lower, the effect is the same as with the massive dam. Now trials have proved that a dam, consisting of vertically arranged bars is most effective in removing those faults, because the 40 open spaces above offer less resistance to the water and the passing material, which cannot settle and block the passage. In issuing, the coals and the stone lumps are

pressed against the trellises. If the latter offer resistance in a horizontal direction as 45 is done by wire nets and perforated iron plates, the stones, which are lifted by the forward stroke of the water, are not thrown back again, because they are not able to move in a horizontal direction, and so ob- 50 struct the dam.

In the accompanying drawing, Figure 1 is a cross section of a coal jigger, constructed in accordance with the invention. Fig. 1^a shows the details of the dam (c). Fig. 2 55 shows a plan view of the jigger.

The jiggling sieve of the compartment (f) Fig. 1 is provided with a stone bed (h). The heaviest rubbles issue through this sieve. The jiggling sieve of the compartment (g) has narrower meshes than the one in compartment (f), and the lighter rubbles (d) are discharged in the compartment above the sieve by means of a discharging device. Between the compartments (f) and (g) are 60 the trellises (c), consisting of vertical bars as shown in Fig. 1^a which keep the bigger stone lumps (h) back in the compartment (f), while the small and light rubbles (d) pass through the apertures into the com- 65 partment (d). 70

I claim:

In combination in a jigger, a sieve compartment, a sieve and a stone bed therein, a dam extending across said compartment 75 and composed of vertical bars extending from the sieve and spaced apart sufficiently to permit forward travel of the material being jiggled, but not sufficiently to permit such travel of the stones. 80

In testimony whereof I affix my signature in the presence of two witnesses.

CHRISTIAN SIMON. [L. S.]
